UNITED STATES PATENT OFFICE.

WILLIAM TWEEDDALE, OF TOPEKA, KANSAS.

METHOD OF SOFTENING AND PURIFYING WATER.

SPECIFICATION forming part of Letters Patent No. 665,286, dated January 1, 1901.

Application filed August 24, 1899. Serial No. 728,363. (No specimens.)

To all whom it may concern:

Be it known that I, WILLIAM TWEEDDALE, a citizen of the United States, residing at Topeka, in the county of Shawnee and State 5 of Kansas, have invented a new and useful Method of Softening and Purifying Water, of which the following is a specification.

This invention relates to improvements in methods of softening and purifying water, 10 and more particularly to that class of methods involving chemical reaction; and it has for its object to combine chemical, electrical, and mechanical action to remove both the insoluble impurities and the normal soluble impurities, both organic and inorganic.

The invention consists in changing both the organic and inorganic substances in solution in the water to an insoluble state in suspension and then by coagulation and aggregation 20 of these impurities to form a coagulum which, being precipitated, carries down all impurities, including bacteria.

Any suitable apparatus may be employed in connection with this method, and in the 25 drawings there is shown an apparatus particularly designed for the softening and purifying of feed-water for steam-boilers.

In the drawings forming a portion of this specification, and in which similar numerals 30 of reference designate corresponding parts in the several views, Figure 1 is an elevation showing two tanks or reservoirs, one of which is broken away to show the location and arrangement of the oxidizers, the water supply 35 and outlet, the drain-pipe, and the air-inlet and automatic water cut-off. Fig. 2 is a detail view showing the oxidizers and their connection with the water-supply pipe, one of said oxidizers being in elevation, one in section, 40 and one partially in elevation and partially broken away, a portion also being shown in section. Fig. 3 is a plan view of Fig. 2, showing the complete oxidizers with the exception of one, which has its web and filling 45 removed.

Referring now to the drawings, 5 and 6 represent two tanks which are similar in form and equipment, and a description of the contents of the tank 5 will apply to the contents 50 of the tank 6. Leading to the tanks is a water-supply pipe 7, having branches 8 and 9 entering the tanks 5 and 6 and above which

they are provided with regulating-valves 10, which are adapted to be operated manually.

Within each tank and connected with the 55 water-supply is a valve-casing 11, containing a float-valve having an operating-float 12, which is adapted to rise and fall with the water in the tank to regulate the flow or cut off the flow of the water-supply.

Connected with the outlet end of the casing 60 11 is a pipe 13, which extends downwardly and along the base of the tank, where it includes T-connections 14, connected with the bottoms of cylindrical casings 15, each of 65 which has a perforated false bottom 17 disposed above the bottom thereof.

Within each casing and concentric therewith is disposed a spiral web 18, the outer 70 end of which is in contact with the inner face of the casing and the several convolutions of which are connected at their upper ends by a cross-piece 19, of metal. The casing and its web are made, preferably, of sheet-iron and form the cathode of an electric battery, of 75 which the anode is a filling 20, of coke or other form of porous carbon, the coke lying between the different convolutions of the web and between the outermost convolution and the inner surface of the casing. Suitable collectors 80 21, having a plate connection 22, are inserted in the coke filling, and to the plates 22 are connected wires leading to the plate 19 of the succeeding casing, thus connecting the several casings or batteries in series. The electrolyte is formed by the water within the 85 tank, or rather by the water in its passage to the tank. A steam-operated injector 25 has a delivery-pipe 26, provided at its upper ends with branches having controlling-valves 27 90 and from which lead pipes 28, which enter the pipes 13 in a downward direction, said injector being constructed on the principle of an injector commonly employed for supplying water to a steam-boiler and which acts to 95 force a supply of air through the pipes 26 and 28 and into the pipe 13 in the direction of the flow through said pipe 13, the air passing, with the water, upwardly and through the oxidizers.

A drain-pipe 30, having controlling-valves, 100 is provided for each tank, and in order to draw the water from the tanks an outlet-pipe 31, entering near the bottom of each tank, has an upwardly-directed connection 32, hav-

ing a float 33 at its upper end and swiveled to the pipe 31, so that said connection may rise and fall under variations in the level of the water in the tank and may thus act to draw the water from a point near its surface.

Having thus described the form of apparatus, the method and its operation are as follows: Having by analysis of the water, verified by direct experiment, ascertained the nature and amount of impurities in solution, I calculate the quantities of reagents required to render insoluble the various salts that are present in solution and to neutralize the acids or alkalies in the volume of water which the reservoir is known to contain and put these quantities of reagents into the tank. The salts to be removed are usually lime, magnesia, and iron in the form of sulfate and carbonate, the presence of which cause hardness when used for washing, incrustation in steam-boilers, and often induce disease when used dietetically. There may also be added a suitable amount of a ferric salt, as ferric chlorid, which by reaction with any hydrates present in or added to the water will result in a gelatinous ferric hydrate, which aids mechanically the separation of impurities in suspension in the liquid. The reagents, the natures of which have been determined by the character of the impurities in the water, are added to the tank. If these impurities are in the form of bicarbonates of calcium and magnesium, the reagent employed may be calcium hydrate or sodium hydrate. If the calcium hydrate is used, the chemical combination of the calcium hydrate with a portion of the combined carbonic acid forms an insoluble carbonate of calcium or magnesium. The tank is then filled with water, which enters through the oxidizers comprising the casing 15, and at the same time air is forced into the pipe 13 and passes through the oxidizers with the water. During the passage of the water through the oxidizers the agitation of the water by the air and the reaction of the oxygen of the air with the ferric reagent, together with the galvanic action of the oxidizers, accomplishes a complete oxidation of the organic matter and the water emerges from the oxidizers practically free from the organic impurities in solution. As the water enters the tank it is thoroughly mixed with the reagents in the tank under the influence of the head of the water and the passage of air therethrough. At the same time the water is agitated by the injected air. After completion of all the reactions to neutrality clay and perchlorid of iron are added and the water is finally agitated. The result is the coagulation of the insoluble impurities,

followed by the aggregation of the insoluble matter forming a condensed mass. This condensed mass being precipitated by sedimentation falls to the bottom of the tank, carrying down with it all insoluble substances. Also the presence of the ferric hydrate, as above described, not only assists in the coagulation, but the oxygen thereof combines with whatever organic matter may be present and oxidizes it, the oxygen being replaced from the injected air.

When the water is clear, it may be drawn off from near the surface by the method above described.

It will of course be understood that any desired reagents may be employed to secure the reactions of the different impurities and that these reagents will be varied in accordance with the nature of the material; also, it will be understood that any desired apparatus for carrying out the several steps of this process may be employed.

Having thus described the invention, what I claim is—

1. The method of softening and purifying water, which consists in aerating the water; oxidizing the organic matter therein by galvanic action; rendering insoluble the salts held in solution and neutralizing the acids and alkalies by means of chemical agents; effecting the coagulation of the insoluble impurities, the said water being kept in a state of agitation during each of the foregoing operations; precipitating the insoluble impurities by sedimentation, thus causing them to sink in mass to the bottom of the water, substantially as described.

2. The method of softening and purifying water, which consists in aerating the water; oxidizing the organic matter therein by galvanic action; rendering insoluble the salts held in solution and neutralizing the acids and alkalies by means of chemical agents; effecting the coagulation of the insoluble impurities by means of chemical agents; keeping the water in a state of agitation during each of the foregoing operations by the passage of a current of air through it; precipitating the insoluble impurities by sedimentation, thus causing them to sink in mass to the bottom of the water, substantially as described.

In testimony that I claim the foregoing as my own I have hereto affixed my signature in the presence of two witnesses.

WILLIAM TWEEDDALE.
